UNITED STATES PATENT OFFICE.

JAMES NACEY, OF MILWAUKEE, WISCONSIN.

VESSEL.

Application filed November 24, 1926. Serial No. 150,468.

This invention relates to vessels and is particularly directed to a sand carrying vessel.

Objects of this invention are to provide a novel form of sand carrying vessel which is so constructed that it can carry a larger quantity of sand for the same external dimensions and draft of the vessel than has heretofore been possible, which does not have bulkheads or beams in the hold, which has a hold open throughout from one end to the other, not practicable with the customary construction in vessels of large dimensions, and which is so constructed that although the vessel may encounter heavy seas, nevertheless shifting of the sand does not occur and, consequently, unbalancing of the vessel with disastrous consequences can not occur.

Further objects are to provide a peculiar form of the sides or walls of the hold which constitute a self-trimmer, inasmuch as the sand gravitates to a restricted area.

Further objects are to provide a sand carrying vessel in which means are provided for extracting or removing the water from the sand, it being understood that the sand and water are together pumped into the vessel in the usual manner, and in which the water may be allowed first to run out of the hold of the vessel by gravity until the water inside the hold approximates the level of the sea, and in which additional means are provided for removing substantially all of the water from the sand, so that the vessel has a lighter load to carry for the same volume of sand than has heretofore been possible.

Further objects are to provide a sand carrying vessel in which means are provided consisting of sumps and wells through which the water may pass and discharge through the bottom of the vessel, eliminating devices on deck, and the shedding of water on same, and in which a series of valves are provided which may be independently controlled to govern the water level in the hold, and in which an emergency valve is provided for permitting the discharge of the water through the side of the vessel in case the vessel settles upon the bottom during filling.

Further objects are to provide a filtering trap which may be operated to remove the water from the sand after the water in the hold has settled to approximately sea level, and to so construct the trap that it will prevent the passage of sand therethrough, but will permit relatively clear water to be drawn from the mass of sand and water in the hold,

so that the vessel is materially lightened, although the total volume of sand carried is materially greater than has heretofore been possible with the same size of vessel.

Further objects are to provide a novel form of framing or bracing and to so construct this bracing that it cooperates directly with the shape of the hold, and generally to provide a sand carrying vessel which is thoroughly safe and seaworthy.

An embodiment of the invention is shown in the accompanying drawings in which:

The several views are diagrammatic and are as follows:

Figure 1 is a fragmentary transverse sectional view through the vessel, such view corresponding approximately to a section on the line 1—1 of Figure 2;

Figure 2 is a transverse sectional view corresponding approximately to a section on the line 2—2 of Figures 1 and 3;

Figure 3 is a sectional view on the line 3—3 of Figure 2;

Figure 4 is a fragmentary sectional view approximately on the line 4—4 of Figure 2;

Figure 5 is a sectional view partly in perspective on the line 5—5 of Figure 4;

Figure 6 is a sectional view partly in perspective on the line 6—6 of Figure 4;

Figure 7 is a fragmentary plan view of one of the sand traps and the associated header.

Figure 8 is a detail of the center keelson and the associated braces.

Referring to the drawings, particularly Figures 1 and 3, it will be seen that the vessel comprises water tight compartments or tanks 1 located on opposite sides of the vessel and extending longitudinally thereof. Between these compartments, the sand receiving hold 2 of the vessel is located. The vessel is formed of outer plating 3, a bottom 4, a main deck 5, and a working deck 6. The hold of the vessel is defined by means of the inwardly slanting upper plates 7 and the outwardly slanting lower plates 8. These plates are joined by an intermediate substantially vertical portion 9. The hold is completed by the bottom 10. The bottom of the vessel is strengthened and made extremely rigid by means of the vertical partitions 11 which are attached to the bottom 4 and the bottom 10 of the hold. These parts are secured by angle irons 12 or in any other suitable and approved manner. Preferably, at regular intervals transverse plates 13 are provided in order to secure a cellular extremely rigid

structure. The water tight compartments 1, or tanks, in addition to the enclosed spaces at the ends of the vessel, are of sufficient capacity to insure the floating of the vessel even if the entire hold is filled with sand or with sand and water, so that it is impossible to sink the boat by overloading.

In order to provide for the requisite lateral strength of the sides 3 of the vessel, angularly arranged channelled struts or shoring braces 11, 12, and 13, are provided. Obviously, more braces may be employed and arranged in this diagonal manner, as desired, the diagonal arrangement being shown in Figure 1. This bracing structure occurs at regular intervals along the boat from one end to the other contiguous to the hold, and provides against inward or outward bending or distortion of the sides 3. It is to be noted that the main diagonal braces or struts 12 and 13 are secured to the slanting lower and upper portions 8 and 7 of the sides of the hold. Preferably, the brace or strut 11 is joined to the brace 13 at its crossing point by means of the roughly rectangular plate 14. Also, it is to be noted that a vertical stanchion 15 extends from the bottom of the vessel to the top, and is secured to the vertical intermediate portions 9 of the walls of the hold. Further, a triangular bracing plate or nucleus 16 is secured to the struts or braces 12, 13, and 15 adjacent their point of crossing.

It is, of course, to be understood that the usual structural formation of horizontally extending beams or angle and channel iron members, as indicated at 17 and 18, are provided, together with suitable reenforcing corner webs 19 and 20. In addition to this, any number of longitudinally extending members 21 may be provided, as desired, and as illustrated particularly in Figure 1. It is to be noted further, that the upwardly extending diagonal braces or struts 13 are joined to the horizontal transverse beams 18 by means of the reenforcing plates 22, and are also joined to the deck 6 by bracket plates 23.

It is to be distinctly understood that other structural bracing members are employed than those specifically recited, but it is believed that a description of the main bracing members is sufficient to illustrate the structural formation of the vessel, and the means whereby the unusual rigidity and strength is primarily attained. At regularly spaced points along the inner side of the hold, sumps and wells 24 and 25 are provided, as illustrated particularly in Figures 1 and 2. These portions are defined by a rectangular inwardly projecting box-like construction. The inner walls of the sumps 24 are indicated by the reference character 26, particularly as may be seen from Figure 1. These inner walls have perforated lower side portions 27 and a perforated lower front or inner

portion 28, such latter portion being hinged, as indicated at 29, for a purpose hereinafter to appear. The sumps 24 are separated from the wells 25 by means of the plates or walls 30, preferably, removable manhole covers 31 being provided in such walls.

Further, it is to be noted that discharge, downwardly extending passages 32 are provided leading from the well to the lower portion of the vessel and opening into appropriately sealed rectangular compartments, as indicated by the reference character 33, in Figure 1. The bottom of the vessel at such last mentioned compartments is perforated or open to the sea, as indicated at 34 in Figure 1. It is to be noted that the sides of the passageways 32 of the wells 25 make a re-entrant angle with the walls 30 dividing the wells from the sumps. In order to prevent water from lodging in these angular compartments, such compartments are filled with cement, as indicated by the reference character 34 so as to give a slanting self-draining surface, as shown particularly in Figure 1.

It is to be noted also from Figure 1 that the walls 30 are provided with a plurality of apertures, as indicated by the reference characters 35, 36, and 37. These apertures are controlled by sliding valves 38, 39, and 40. The position of these valves is controlled in turn by means of the hand wheels 41, 42, and 43, which are accessible from the deck 6. These hand wheels are connected by means of threaded spindles and sleeves, as shown in Figure 1, with their respective valves, so that the valves may be independently controlled. These valves, therefore, control communication between the sumps 24 and wells 25. Further, it is to be noted that the side walls of the wells 25 are provided with openings 44 which are, in turn, controlled by valves 45. These valves are operated by means of hand wheels 46 in a manner similar to those previously described and, consequently, such last mentioned valves 45 control communication directly between the hold and the wells.

It is to be noted further that the wall 9 is apertured and is connected to an apertured portion of the outer wall 3 of the vessel by means of a pipe 47. Communication from the wells 25 to the pipes 47 is controlled by means of the valves 48 which may be termed emergency valves, as will appear hereinafter, such valves being controlled by hand wheels 49, as shown in Figure 1.

The sand and water is pumped into the hold through headers 50, such headers having branch pipes 51 discharging into the hold and controlled by valves 52. These valves are operated by hand wheels 53, also accessible from the deck 6.

In the operation of this vessel, the sand and water is pumped through the large headers 50 and is distributed in the proper manner through the branch pipes 51, the actual dis-

tribution along the held of the vessel being controlled by the setting of the valves 52. The sand builds up in the bottom of the hold and some of the sand passes through the perforated portions 27 and 28 into the lower portion of the sumps 24 where it lodges and forms a natural filter for the water to pass through thereafter. For a relatively low level of the water within the held, the lowermost valve 10 38 is opened and allows the water to flow through the apertures 35 into the wells 25. If the water in the held is above the sea level, it is apparent that the water will run downwardly through the passages 32 from the wells 15 34 and outwardly through the perforations 34 in the bottom of the vessel. As the loading increases, the valve 38 may be closed and the valve 39 opened, the action previously described continuing. Finally, the valve 39 20 may be closed and the valve 40 opened.

If it is found that the vessel inadvertently settles upon the bottom and closes the apertures 34 during loading, this condition will be immediately indicated by the relatively 25 rapid rising of the water in the held. Under these conditions, the supply of water and sand is shut off and the emergency valves 48 are opened. This allows the wells 25 to discharge through the pipes 47. The water 30 rises upwardly through the sand which partially fills the lower portion of the sumps 24 and flows into the wells 25 and from thence passes outwardly through the pipes 47. This operation, however, can be hastened if the 35 sand is below the valves 45, by opening the auxiliary valves 45 and allowing water to flow directly from the held into the wells 25 and from thence outwardly through the pipes 47. This quickly allows the vessel to rise from 40 the bottom and, consequently, to open the perforations 34 in the bottom. When this occurs, the emergency valves 48 are closed, as well as the auxiliary valves 45, and the operation 45 of loading continues as before, after having shifted the position of the vessel.

It is to be noted that approximately, the sand fills from 75 to 60% of the space in the held under usual conditions, the voids or spaces between the sand constituting from 25 50 to 40%, and being filled with water.

In order to lighten the load of the vessel and confine its load substantially wholly to the weight of the sand, the action previously described of separating the water and sand 55 is supplemented by the action of sand filtering traps which will now be described, it being understood that the valves 38, 39, 40, 45, and 48, are all closed.

Referring to Figures 2 and 4 to 6, it will 60 be seen that the slanting side walls or lower portions 8 of the held are provided with apertures 54 adjacent their lower portions and very close to the bottom of the held. These apertures communicate with sand traps, indicated generally by the reference character

55. These sand traps consist of box-like structures, as shown in greatest detail in Figures 4, 5, and 6. Preferably, the hole 54 is rectangular and a rectangular short length of pipe 56 leads therefrom to the appropriate 70 sand trap.

Referring particularly to Figures 4, 5, and 6, it will be seen that the sand trap consists of a downwardly extending channel 57 which communicates at its lower end with an upwardly extending channel 58. This upwardly extending channel 58, in turn, communicates with a downwardly extending channel 59, as developed by the perspective sectional views shown in Figures 5 and 6, and so by the arrows associated with such figures. The downwardly extending channel 59 opens at its lower end into an upwardly extending channel 60 which, in turn, communicates at its upper end with a downwardly extending 85 channel 61. In turn, this downwardly extending channel communicates at its lower end and with an upwardly extending channel 62. It is to be noted that this last channel communicates by means of a pipe 63 (see Figure 7) with the clear water header 64.

The action of these sand traps is as follows: The sand and water pass downwardly in the first channel 57 and rises part way in the second channel 58. The water flows through 95 this sand something on the order of a filtering action taking place, and passes successively downwardly and upwardly through the remaining channels, finally clear water being discharged through the pipe 63 wholly freed 100 from sand. This clear water is received by the collecting clear water header 64, such header passing to suitable pumps and removing the water. The reason for providing a plurality of channels 57 to 62 is to insure the 105 collecting of the sand in one or more of the channels and to guard against discharge of sand into the clear water headers, it being understood that the series of sand traps is duplicated on opposite sides of the vessel. 110

This filtering action may continue for the requisite length of time until substantially all of the water is removed from the spaces between the grains of sand, so that the vessel is called upon to carry only a weight equal 115 to that of the sand itself, and is not loaded down by the unnecessary weight of the water, as in the usual practice.

It is to be distinctly understood that any number or combination of channels, as described above, may be employed in the sand traps, preferably however, a sufficient number is employed to insure retention of the sand. Further, it is apparent that by making the channels rectangular in cross section, that a very compact arrangement for the sand traps may be secured.

When the vessel arrives at the place for discharging the sand, it is clear that any suitable type of unloading mechanism may be 130

projected into the open hold of the vessel and may traverse such hold from end to end, without interruption, as there are no transverse braces or bulkheads crossing such hold. 5 Consequently, the utmost ease of discharging the sand is secured by this construction.

Due to the peculiar manner of forming the vessel, as described in the first portion of this specification, it is clear that the transverse 10 deck beams and bulkheads heretofore found indispensable in the usual designs of sand carrying vessels, are wholly unnecessary as a measure of safety with the type of vessel forming the subject matter of this invention, 15 as the vessel is a rigid unit throughout, without the necessity of such transverse braces or bulkheads in the hold.

It will be seen further, that the draft of the vessel for the same volume of sand is materially less than has heretofore been possible 20 in sand carrying vessels for the same size and the same capacity of hold, as means are provided for removing the water from the sand so that the vessel, as stated above, is called 25 upon to bear only the actual weight of the sand, while it is transporting the load. Further, it is to be distinctly understood that the water-tight compartments or tanks 1 may be divided by plates or bulkheads into any number 30 of distinct compartments.

Further, it is to be noted that the buoyancy 35 of the water-tight tanks or compartments is sufficient to prevent sinking of the vessel, even when the hold is completely loaded with sand or with sand and water. Further, due to the 40 fact that there is no open communication whatsoever between the hold and these watertight compartments, irrespective of the opening or closing of any of the valves, it is apparent 45 that the vessel will not sink even if any of the valves are inadvertently left open, as no damage can be done by such inadvertence.

It is to be noted that the bracing of the 50 ship at the center keelson is illustrated in Figure 8 and partially in Figure 1. The center keelson 65 is joined to the plates 13' in the usual manner. However, in order to continue 55 the bracing of the ship so as to adapt it for the handling of sand in a hold without transverse braces or bulkheads, an additional and novel form of bracing is employed. This bracing consists of the slanting or diagonal 60 bracing members 66 which are secured at their outwardly turned ends 67 to the center keelson 65, and are similarly secured at their ends 68 to the plates 13'. Four of these bracing members are employed at each point of crossing of the center keelson and the plates 13'.

It will be seen that this novel form of construction greatly increases the strength of the vessel.

It will be seen, therefore, that a highly 65 practical and easily constructed sand carry-

ing vessel has been provided by this invention, which is a rigid unit and is yet devoid of transverse braces or bulkheads in the sand carrying hold. Further, it is to be noted that the vessel is thoroughly seaworthy, and 70 although it may encounter rough seas and roll to a great extent, that nevertheless displacement of the sand in the hold can not occur due to the outwardly bulged formation of the side walls of the hold. The sand, it is to be 75 noted, will pack or pocket in these outwardly bulged portions and, consequently, can not be washed from one side to the other side during the rolling of the vessel. Consequently, shifting of the load can not occur 80 and the utmost stability is secured. Further, it is to be noted that due to the fact that the water has been removed from the sand, such sand more readily packs than heretofore and the shifting of the sand is further prevented 85 by this means.

In addition to the results previously stated, it is to be noted that if it should happen through stress of weather that any of the sand were lost overboard the resulting space 90 would be filled with sea water, a much lighter substance, in consequence of which the vessel's draft would be decreased.

It is to be noted that the pivoted perforated 95 portions 28 permit cleaning of the sumps when the hold is empty.

Further, it is to be noted that a highly practical and easily controlled means has been provided for removing the water from the sand, so that the load of the vessel for the 100 same volume of sand is materially lightened.

It is to be noted further that all of the values are readily under the control of the operators positioned upon the deck 6, and that the utmost ease of control of the various 105 members is thus secured.

Although the invention has been described in considerable detail, such description is intended as illustrative rather than limiting as the invention may be variously embodied and 110 as the scope of such invention is to be determined as claimed.

I claim:

1. A sand carrying vessel comprising an outer shell and an inner shell forming a sand carrying hold and spaced from said outer shell, a plurality of compartments, one set of compartments communicating at their lower ends with the said hold and communicating at intermediate points with the other set of said compartments, the other set of said compartments opening through said outer shell, whereby water carried by the sand in the hold will pass upwardly into the first of said compartments and into the other of said compartments and outwardly through the outer shell until the level of the water in the hold approximates sea level.

2. In a sand carrying vessel, the combination of an outer shell and an inner shell form-

ing a hold adapted to have sand and water pumped therein, primary means for continuously separating the water and sand during the filling of the hold and allowing the water 5 to flow by gravity and discharge outside the outer shell, and auxiliary filtering means for separating practically all of the water remaining in the sand after the filling of the hold has been completed, whereby the vessel 10 is relieved of the majority of the weight of the water after the hold has been filled.

3. A sand carrying vessel comprising an outer shell and an inner shell forming a sand carrying hold adapted to have sand and water 15 pumped therein, said vessel having compartments forming sumps and wells, said sumps opening at their lower ends into the lower portion of said hold, said wells opening through the bottom of said outer shell, and 20 means for controlling communication between said sumps and wells.

4. A sand carrying vessel comprising an outer shell and an inner shell forming a sand carrying hold adapted to have sand and water 25 pumped therein, said vessel having compartments forming sumps and wells, said sumps opening at their lower ends into the lower portion of said hold, said wells opening through the bottom of said outer shell, means 30 for controlling communication between said sumps and wells, and auxiliary means for providing emergency discharge passages from said wells through the sides of the outer shell.

5. A sand carrying vessel comprising an outer shell and an inner shell forming a sand carrying hold, said vessel having pairs of compartments forming sumps and wells, said sumps having the lower portion of their walls 40 provided with a plurality of apertures opening into the lower portion of said hold, means for placing said sumps and wells in communication with each other at points above the lower apertured portions of said sumps, said 45 wells extending downwardly to the bottom of the outer shell, the bottom of said outer shell having perforated portions adjacent the bottom of the wells.

6. A sand carrying vessel having an outer 50 shell and an inner shell forming a sand carrying hold, a plurality of vertical units arranged along the sides of said hold and each having two compartments forming respectively a sump and a well, valves controlling 55 communication between said sumps and wells, the lower portion of said sumps communicating with the lower portion of said hold, said wells opening through the bottom of said outer shell, pipes opening into said 60 wells and opening through the sides of the outer shell, and valves controlling said pipes.

7. A sand carrying vessel having an outer 65 shell and an inner shell forming a sand carrying hold, a plurality of vertical units arranged along the sides of said hold and each

having two compartments forming respectively a sump and a well, valves controlling communication between said sumps and wells, the lower portion of said sumps communicating with the lower portion of said hold, said wells opening through the bottom of said outer shell, pipes opening into said wells and opening through the sides of the outer shell, and valves controlling said pipes, said vessel having a deck, and all of said 70 valves being controlled from said deck.

8. A sand carrying vessel having an outer shell and an inner shell forming a sand carrying hold, a plurality of vertically arranged units positioned along the sides of said hold 80 and each consisting of a sump and a well, said sump having a perforated lower portion communicating with the lower portion of said hold, a plurality of valves adapted to establish communication between said sumps 85 and wells at any of a plurality of vertically spaced points, said wells opening through the bottom of said outer shell, pipes extending from said wells and opening through the sides of said vessel, valves controlling said 90 pipes, and a plurality of auxiliary valves adapted to establish communication directly between said hold and said wells.

9. A sand carrying vessel having an outer shell and an inner shell forming a sand carrying hold, a plurality of vertically arranged units positioned along the sides of said hold and each consisting of a sump and a well, said sump having a perforated lower portion 95 communicating with the lower portion of said well, a plurality of valves adapted to establish communication between said sumps and wells at any of a plurality of vertically spaced points, said wells opening through the bottom of said outer shell, pipes extending from said wells and opening through the sides of said vessel, valves controlling said 100 pipes, and a plurality of auxiliary valves adapted to establish communication directly between said hold and said wells, the perforated lower portions of said sumps being 105 movably mounted to permit cleaning of said sumps and wells when said hold is empty.

10. A sand carrying vessel having a hold into which a mixture of sand and water is 115 adapted to be pumped, and filtering traps communicating with the lower portion of said hold and adapted to arrest the passage of the sand while permitting the withdrawal of the water through such traps, said filtering traps each having a plurality of communicating reversely extending passage- 120 ways.

11. A sand carrying vessel having a hold and having pipes leading to said hold and 125 adapted to convey sand and water into said hold, a plurality of filtering traps communicating with the lower portion of said hold at spaced points, each of said traps having vertical channels communicating in succession 130

with each other at alternate ends, and a discharge pipe connected to said filtering traps and communicating with the last of the channels of said traps, whereby sand will be retained in said channels while permitting the withdrawal of water through said channels.

12. A sand carrying vessel comprising an outer shell, an inner shell spaced from the outer shell and forming a sand receiving hold, the side walls of the inner shell being outwardly bulged to form concavities in which the sand is adapted to pocket, diagonal bracing members extending from the outer shell to the inner shell and secured to the side

walls of the outwardly bulged hold, said vessel having a center keelson and transverse plates secured at their points of crossing, and bracing members extending angularly from the center keelson to the transverse plates and arranged in groups about each point of crossing of the center keelson and transverse plates and secured to such keelson and transverse plates. 20

In testimony that I claim the foregoing I 25 have hereunto set my hand at Milwaukee, in the county of Milwaukee and State of Wisconsin.

JAMES NACEY.
